BRASSIÈRE

Ann Arons Alberts, New York, N. Y.; Leon N. Alberts, executor of Ann Arons Alberts, deceased

Application February 11, 1937, Serial No. 125,207

5 Claims. (Cl. 2—42)

This invention relates to garments for women. It has for its object to provide a garment such as a brassière, corset or the like which will give better and more natural support to the bust with a greater degree of comfort than is obtainable with such garments as heretofore constructed, and which will eliminate any tendency to impair the health because of improper support.

A further feature of the invention is to provide a snug fit beneath the bust to prevent the garment from working upward, and also to provide a snug fit at the sides so as to prevent the gaping of the upper edge of the brassière away from the body.

Another object of the invention is to cause the garment to hug the body tightly in the center at the front so as to give emphasis to the natural feminine figure.

The invention also aims to confine the flesh at the sides of the bust and to improve the bust line of unsymmetrical figures.

In most garments of this kind as heretofore made, the breasts were confined within pockets in the garments by the tension of the body-en-circling portion of the garment and by shoulder straps attached to the upper edge of the garment over the centers of the pockets. By means of the construction of the present invention the tight drawing over the fronts of the breasts which is unavoidable with garments constructed as above mentioned, is eliminated, and yet the desired "up-lift" or supporting and lifting of the breasts from beneath is obtained.

Attempts have been made heretofore to make such garments more comfortable by providing an inner section which is free and disconnected from the main or band portion of the brassière except at selected points of connection therewith, this inner section forming so-called bust supporting and receiving "pouches". The upper edges of these pouches, however, had a tendency to produce a sharp line of pressure underneath the breasts which tended to make the garments uncomfortable. This difficulty is entirely overcome by the construction of the present invention.

In other previous efforts to render these garments more acceptable the material forming the pockets was reinforced or stiffened with the intention that the pull of the shoulder straps extending upwardly centrally of the breasts would be prevented from drawing tightly over the front. The desired comfort, however, cannot be secured in a garment of this sort where the material in direct contact with the breasts is provided with stiffening means.

The invention will be better understood by con-

sidering the accompanying drawings which illustrate, by way of example two embodiments of the invention.

In these drawings:

Fig. 1 is an inner or rear view of the improved 5 brassière;

Fig. 2 is an outer or front view;

Fig. 3 is a perspective view showing the garment as it is worn;

Fig. 4 is a detailed view of a portion of the garment intended to illustrate the action thereof in supporting and lifting the breast;

Fig. 5 is a sectional view taken on line 5—5 of Fig. 3; and

Fig. 6 is a view similar to Fig. 2 showing a modification.

Referring now to these drawings, the brassière comprises a band 1, adapted to encircle the body in the region of the bust, together with shoulder straps 2 and 3 and suitable connections between 20 the ends of these straps and the band portion. The band portion 1 consists of two front sections 4 and 5 and two side sections 6 and 7, these latter extending around the body and partially across the back, as is customary in garments of this 25 kind. The garment is held in place by fasteners 8, connected together by an elastic extension 9 being inserted to make the garment fit snugly.

The portions 4, 5, 6 and 7 are made of soft, pliable fabric but which has comparatively little 30 "give" or stretch. The front sections 4 and 5 are stitched together along a vertical seam 10 and to the side sections 6 and 7 respectively by means of seams 11 and 12. These seams are preferably covered with suitable tape in the usual manner, 35 as well as the seam 13 which extends along the bottom of the garment.

The front sections 4 and 5 are given shape as desired by means of darts 14 in order to embrace the lower portions of the breasts of the wearer. 40 The upper portions 15 are preferably made of a light material such as net or lace and may be pointed at the top in the usual manner.

The shoulder straps 2 and 3 are made of relatively inelastic material such as ribbon but may be 45 provided with elastic inserts 16, preferably at the back.

The front ends of the shoulder straps, instead of being attached to the tops of the net portions 15, in such a manner that the support given by 50 the straps to the breasts would produce tension over the fronts of the breasts, are attached to the front sections 4 and 5 at the sides of each section, by means of angular straps 17 and 18. These side straps 17 and 18 are of relatively in- 55

extensible material similar to that of the shoulder straps. The upper portions 15 are held up by means of elastic connections 19 between the shoulder straps and the upper edges of these upper portions. Upper portions 15 serve more as mere coverings for the upper portions of the breasts than as confining means, and the elastic connections are merely to hold these cover portions in place.

10 Side straps 17 and 18 are preferably connected to the shoulder straps in such a manner as to at least partially equalize the tension in the two straps and permit of lateral shifting as the wearer bends or twists sidewise. Thus, for 15 example, the straps 17 and 18 may conveniently be made of a single piece of ribbon material sewed at their ends to the upper edges of the front sections 4 and 5 with the central portion passing through a slide member 20 secured to 20 the end of the shoulder strap.

When the garment is in position on the body of the wearer the seam 13 encircles the body just below the bust line, and the front sections 4 and 5 extend upwardly beneath the breasts from this 25 seam to approximately the horizontal center line of the bust, as may be seen in Figs. 3 and 5. The centers of the upper edges of sections 4 and 5 are located just below the centers of the breasts while at the sides thereof these edges may be 30 and are preferably somewhat higher. These sections 4 and 5 under the tension of the seam 13 and the side straps 17 and 18 consequently form a sort of soft cradle extending beneath the breasts, within and upon the upper surface of 35 which the lower portion of each breast rests. When the garment is put in place, therefore, by the wearer, the breasts are not only lifted to a uniform elevation, but also the flesh at the base of the breasts, particularly on the lower 40 sides thereof, is urged outwardly filling the outer portion of the cradle-like members 4 and 5 and being lifted into light contact with the upper portions 15.

This is illustrated in the drawings in Fig. 4, 45 where the dotted and somewhat circular line indicates the approximate outline of the breast (viewed from the front) before the garment is applied, and the smaller dotted approximately circular line indicates the location of the base 50 of the bust after the garment is in position. The positions of the side straps 17 and 18, before the garment is secured on the body of the wearer, are shown in dotted lines, and the positions which these straps assume after positioning the garment are shown in full lines. The arrows also 55 indicate that as tension is applied to the side straps 17 and 18 during the application of the garment to the body of the wearer, the lower ends of these straps swing toward one another showing 60 that the lifting of the flesh into position to fill the outer portion of the recesses formed by the front supporting sections 4 and 5 and the cover section 15 causes the base of the breast to be reduced in diameter. A drooping figure is 65 thereby moulded to accomplish the desired youthful bust line.

The lifting of the breasts, however, by the shoulder straps 2 and 3 is accomplished by means of these side straps 17 and 18 which extend 70 around well to the sides of the breasts, as may be seen in Fig. 3, so that these straps have very little curvature in the front direction and consequently do not press undesirably against the body of the wearer. From Fig. 3 it will be seen 75 that these straps 17 and 18 are very nearly

straight when in actual position when the garment is in place. Furthermore, this lifting action of the straps 17 and 18 is entirely independent of the upper or cover portion 15. The amount of pressure exerted by these cover portions 15 over the fronts and upper portions of the breasts is controlled by the length and stretchability characteristics of the elastic connections 19. Hence the garment can be readily constructed to provide any desired degree of looseness or 10 firmness of the upper cover portions 15.

Referring now to Fig. 6 of the drawings, there is here illustrated a modified form of my improved garment which is similar in construction to the garment above described, except in one 15 respect, namely, in the form of extensible connection between the shoulder straps and the upper or cover portions 15. Instead of providing an elastic connection such as the connection 19 shown in the previous figures, the garment of Fig. 20 6 has a connection 21 which is adjustable in length. This may be arranged in any convenient manner, but I have shown a strip of tape, or ribbon material, 22 secured to the shoulder strap 2 at the rear of slide 20, the lower end of this 25 strip passing through an eye 23 attached to the point of the cover portion 15 and the strip terminating in a slide 24 which may be moved up and down on the strap in a well known manner.

When the extensible connection takes this form 30 the strip 22 may be of inelastic material, and the cover members 15 may be adjusted to a comfortable position by adjustment of the slide 24. This adjustment is independent of the support 35 of the front sections 4 and 5 by the side straps 17 and 18. An adjustable elastic connection may, of course, be employed if desired, by making the strip 22 of elastic webbing.

The brassière of the present invention might be called a bandeau for stout women, since the 40 garment is constructed as is the ordinary bandeau which is intended for the more slender or youthful figures. The support of the lower portions of the bandeau beneath the breasts by means of the side straps 17 and 18, however, independently of the support of the cover portions 45 15 enables the bandeau to be successfully and comfortably worn by large persons.

I claim:

1. In a garment of the class described, a band 50 of soft flexible material adapted to encircle the bust having a pair of outwardly-extending, generally-conical recesses at the front to receive the breasts, each of said recesses including a lower breast-supporting portion and an upper cover portion, shoulder straps extending upwardly centrally of the recesses and connecting means for each shoulder strap comprising a pair of side straps secured at their lower ends to the band at the sides of the recesses at places substantially in horizontal alignment with the centers thereof, said straps having their upper ends secured to the shoulder strap, and an extensible connection 55 between the upper portion of the band and the shoulder strap, whereby the side straps are caused to support the lower portion of the band beneath each breast thereby lifting the breasts and at the same time drawing them inwardly at the sides and causing them to conform to the shape of the recesses without applying tension over the front 60 of the breasts.

2. In a garment of the class described, a band 65 adapted to encircle the bust having a pair of outwardly-extending, generally-conical breast receiving sections each comprising a cradle por- 70

- tion and a cover portion, a pair of shoulder straps, and means for connecting the front end of each shoulder strap to one of the cradle portions comprising a pair of side straps secured at their lower ends to the sides of the cradle portion at places substantially in horizontal alignment with the centers of said breast-receiving sections, said straps having their upper ends secured to the shoulder strap, and an extensible connection 5 between the upper part of each cover portion and its shoulder strap, whereby the side straps and cradle are caused to support the breasts at the same time pulling them each inwardly at each side thereby causing them to conform to the shape of the breast receiving sections without 10 applying tension over the front of the breasts.
3. In a garment of the class described, a band of soft flexible material adapted to encircle the bust having a pair of outwardly-extending, generally-conical recesses at the front to receive the breasts, each of said recesses including a lower breast-supporting portion and an upper cover portion, shoulder straps extending upwardly centrally of the recesses and connecting means 15 for each shoulder strap comprising a pair of substantially inelastic side straps secured at their lower ends to the band at the horizontal sides of the recesses and having their upper ends secured to the shoulder strap, and an adjustable connection between the upper portion of the band and the shoulder strap, whereby the side straps are caused to support the lower portion 20 of the band beneath each breast thereby lifting the breasts and at the same time drawing them inwardly at the sides and causing them to conform to the shape of the recesses without applying tension over the front of the breasts.
4. A garment of the class described comprising a band adapted to encircle the bust having a pair of breast-receiving sections, a pair of shoulder straps, a pair of substantially inelastic connecting straps secured at their lower ends to 25 the horizontal sides of each breast-receiving section and extending upwardly and attached to one of the shoulder straps, and an elastic connection between the upper portion of each breast-receiving section and its shoulder strap 5 whereby the side straps will support the lower portion of the band beneath each breast and thereby lift the breasts and at the same time draw them inwardly at the sides and cause them to conform to the shape of the recesses without applying tension over the front of the breasts, and the elastic connections will hold the upper portion of the breast-receiving sections over the breasts without applying appreciable pressure 10 against the breasts.
5. A garment of the class described comprising a band to encircle the bust having a pair of breast-receiving sections, a pair of shoulder straps whose back ends are attached to the bands, and means for connecting the front portion of each shoulder strap to one of said sections comprising a pair of substantially inelastic side straps secured at their lower ends to the horizontal sides of each breast-receiving section and extending obliquely upwardly and having a slide- 20 able equalizing connection for attaching their upper ends to the forward portion of their shoulder strap, and an elastic connection between the upper portion of each breast-receiving section and its shoulder strap, whereby the side straps 25 will support the lower portion of the band beneath each breast and thereby lift the breasts and at the same time draw them inwardly at the sides and cause them to conform to the shape of the recesses without applying tension over the front of the breasts, and the elastic connections will hold the upper portion of the breast-receiving sections over the breasts without applying appreciable pressure 30 against the breasts.
- 40

ANN ARONS ALBERTS.
